STEAM GENERATING SYSTEM

Charles A. French, Riverside, Ill.

Application June 15, 1933, Serial No. 675,935

2 Claims. (Cl. 122—451)

This invention relates to a steam power plant. More particularly it relates to regulating and controlling means for a power plant utilizing a boiler of the semi-flash type.

5 A principal object of the invention is to provide a steam generating plant in which the steam is generated and, after doing its work, condensed at substantially the rate at which it is being used.

10 Another object is to control the generation of the steam by inherent means natural to the design and proportions of the system so far as possible so that the automatic control devices may be reduced to the smallest possible number and positive in action and simple in construction.

15 Another object is to provide a condensing system in which amounts of steam in excess of the capacity of the condenser may be condensed for short intervals.

20 Another object is to secure the best possible economy of the auxiliary engine.

Another principal object is to operate an auxiliary engine which is connected to the various auxiliary units of the system including the feed water pump, the condenser fan, and the blower for the burner, by steam supplied from a mid-point of the stroke in the main engine, whereby power developed by the auxiliary engine and, as a result, the power applied to said auxiliaries is proportional to the load on the main engine.

25 Another object is to provide means to remove solids from the boiler feed water before they can become attached to the heating surface.

30 Another object is to provide means for the storage of a large amount of water up to the full boiler pressure and temperature in such a manner that such storage reservoir will occupy waste space and that the reservoir will retain steam pressure enough to start the plant even after standing many hours.

35 Another object is to make it certain that there can be no fire in the burner when a predetermined amount of water is not going through the coils.

40 The objects of the invention are attained by a construction as illustrated in the single figure of the drawing.

45 A main engine 1 is provided with a bleeder or check valve 2 situated at about mid-stroke of the piston 1' from which the partially expanded steam, in quantities and at pressures dependent upon the load on the main engine, escapes through a bleeder pipe 3 to the auxiliary engine 4, where it is used to drive a feed pump 5 by means

5 of gears 6 and 7. The auxiliary engine 4 is also connected by a belt 7' on a pulley carried by the gear 7 to a pulley 8' on a shaft 9'. Said shaft extends into the housing surrounding the burner 8 for operating the blower of said burner. The shaft also carries a condenser fan 10' positioned to direct a blast of air over the condenser, to be herein-after described.

It is intended that the feed pump 5, condenser 44 and burner 8 shall be so proportioned that they shall have correct quantitative relationships, so that whatever the speed of the auxiliary engine, due to the load on the main engine, the burner 8, boiler 10, and feed pump 5 shall furnish steam at practically constant pressure and temperature and at substantially the rate at which it is being used by the main and auxiliary engines, and that the condenser shall condense all, or some practically constant percentage of the exhaust steam. As it is difficult to design pumps and burners that will remain in a fixed quantitative relationship to each other, means are used to vary the quantity of water as needed.

55 The feed pump 5 forces water into the feed pipe 13 and preheating coils 14, where it travels toward the fire, gradually absorbing heat until it passes to the tickler coil 15, which is of the same small diameter as the preheating coils 14, and it has but two or three turns, but, as it is situated nearest the fire, a small amount of water, say 15 percent, is evaporated to steam and the mixture of steam and water passes through the check valve 16 into the settling and regulating drum 17, which may be either above or below the boiler. The mixture of steam and water enters the top of the drum, preferably at a tangent. A cylindrical baffle member 17' is shown mounted in the casing 17 spaced from the top and bottom and side walls thereof and open at the bottom for the flow of liquid.

40 The evaporator feed pipe 18, located within the member 17', starts from any point in the drum above which it is desired to carry the water level; in any case, far enough above the bottom to make it certain that no solids will be drawn from the bottom of the drum where they settle after coming out of solution in preheating the coils 14 and the tickler coil 15. The evaporator feed pipe is fitted with a steady and tight valve 19, which prevents slugs of water entering the evaporator coil, upon any sudden violent pressure reduction in the latter and also prevents the escape of heat and loss of pressure, except through lagging, when the plant is not in operation for extended periods, so that steam is available for

starting after a shut down of many hours. The check valve 20 prevents the water returning from the evaporating coil 21 to the drum. The water is completely evaporated in the coils 21, the steam is superheated in the coil 22, and the steam then passes through the pipe 42 to the throttle valve 23 and to the main engine 1.

It is intended that the pump 5 shall be able to pump somewhat more water than the burner can evaporate, but that a part of it shall be by-passed until the pump is normally furnishing the boiler with, say, 90 percent of the water needed.

It is obvious that the volume of steam entering the drum 17 from the tickler coil 15 is greater than the volume of water leaving the drum 17 through the evaporator feed pipe 18. Therefore, the pressure in the drum 17 is periodically, somewhat more than the pressure in the evaporating coils 21 and superheating coil 22. As the supply of water in the coil 21 becomes somewhat reduced, the pressure falls to the point where it is less than that in the drum 17 when water enters the evaporating coil 21 until the pressures are practically balanced when the flow ceases and for a short time the pressure in the evaporating and superheating coils is greater than in the drum; during such a period no water can flow. The tickler coil is normally making a substantially constant percentage of its water into steam, due to its fixed evaporating surface, while in the evaporating and superheating coils the relationship between superheating and evaporating surfaces is constantly changing, due to the somewhat periodic water feed. The valve 19 prevents these fluctuations being violent.

So long as there is water within reach of the pipe 18 in the drum 17, the action will be as described and the pump will be supplying 90 percent of the water needed. When the water falls in the drum 17 to the point that no more can be furnished the evaporating coils 21, the pressure in the whole boiler will quickly fall to a predetermined point, due to reduction of evaporating surface and loss of the water seal in the drum 17, which maintained a periodic pressure difference between the drum and the coils 21 and 22.

When the pressure has fallen to a predetermined point, the spring 24 overcomes the siphon 25 in the casing 26, the upper side of which is supplied with evaporating coil pressure through the pipe 28. Said siphon contracts, allowing the valve rod 27 to rise, thus allowing the ball 28 to seat, which prevents by-passing of water from the feed pump 5 through the pipe 29 to the suction pipe 30. This causes the entire amount of water delivered by the pump, except a very small amount of water being by-passed through the valve 31 in the by-pass pipe 30, whose function will be later described, to pass into the boiler, causing the water level in the drum 17 to rise until the evaporating coils 21 are again supplied with water. This increased quantity of water entering the tickler coil 15 considerably reduces its normal steam making capacity, thus allowing considerable accumulation of water in the drum 17 before enough water has reached the evaporating coils 21 to allow them to restore the pressure to normal. If the feed pump is at, say, 100 percent over capacity and the valve 19 is considerably throttled, the water level will rise considerably over the bottom of the pipe before there is pressure enough in the evaporating coils 21 to cause the siphon 25 to expand, overcoming the spring 24 and forcing from its seat the ball 28 against the spring 24 and by-pass adjusting screw

33, thus allowing the predetermined excess of water to escape past the ball 28 into the by-pass chamber 34 and the pipe 29 to the suction pipe 30.

To make it certain that there shall be no fire unless there is a predetermined amount of water entering the boiler, water under pump pressure in the pipe 35 from the delivery side of the pump 5 passes to the pipe 37, which communicates with the siphon 38, which, if the pressure is sufficient, causes the siphon 38 to expand against the spring 40 and open the burner air valve 41. The siphon will remain expanded and the air valve open so long as the pump maintains a sufficient supply of water to sustain a predetermined pressure against the adjustable leak valve 31, which is necessary to relieve the pressure in the siphon when water is not being pumped or not pumped in sufficient quantities to keep the siphon expanded.

It is understood that a piston or a diaphragm might be substituted for either siphon above mentioned without changing the action or result.

As long as steam is being supplied to the main engine 1, the auxiliary engine 4 will operate at a speed exactly proportionate to the amount of steam being used by the main engine, and the feed pump 5, the burner 8, and the condenser fan 10 will operate and have capacities substantially in a fixed ratio to the steam used in the main engine. If the steam to the main engine is shut off, the auxiliary engine, the feed pump, burner and condenser will also stop, unless it is desired that the auxiliary engine be kept turning over very slowly, when steam from the main steam line 42 may be admitted through the valve 42' to keep the auxiliary engine moving. If the night valve 14 is closed when the plant is put out of operation, it may be re-started at any time, so long as steam pressure enough to run the auxiliary engine remains in the drum 17, by the use of the throttle valve 42.

The condenser 44 has its outlet 45 extended into the water supply tank 46 near the bottom thereof. The nozzle 47 on the end of the outlet pipe 45 discharges the water and any uncondensed steam into the throat of the mixing tube 48, thereby causing a very intimate mixing of any uncondensed steam with the water in the tank, so that its heat may be given off to the water and it cannot pass to the atmosphere as steam. This serves to save the water that would be otherwise lost if it were decided to make the condenser fan of a size and speed that it would only furnish enough air for condensation of the steam used at normal load. This ejector condenser action becomes less efficient as the water in the tank rises in temperature, and is only intended to care for temporary overloads.

It is to be understood that applicant has shown and described only one embodiment of a steam generating plant embodying his invention and that he claims all modifications falling within the scope of the appended claims.

What is claimed is:

1. A steam power plant comprising a boiler and burner casing, steam generating coils mounted in said casing, a storage drum connected to said coils, said drum being divided into compartments communicating below liquid level, the discharge end of one coil communicating with one compartment of the drum above the normal liquid level therein, the outlet to another coil communicating with another compartment of the drum below the normal liquid level therein, and means for supplying feed water to one of said coils.

2. A steam power plant comprising a boiler and burner casing, a storage drum divided into compartments communicating with each other below the normal liquid level therein, a preheating and steam generating coil positioned in the casing and having its discharge end connected to the drum

above the normal liquid level, means for supplying feed water to said coil, and a steam generating coil located in the casing, the inlet end of said coil being connected to a second compartment of the drum below the liquid level therein.
